UNITED STATES PATENT OFFICE.

RALPH R. SMITH, OF JACKSON HEIGHTS, NEW YORK, ASSIGNOR TO NATIONAL CARBON COMPANY, INC., A CORPORATION OF NEW YORK.

TUMBLER SWITCH.

Application filed November 3, 1925. Serial No. 66,607.

This invention relates to electric switches particularly adapted for battery operated electric hand lanterns, hand lamps, and the like. Some or all of the features of this switch may be used in other circuits of low voltage and wattage.

The principal object of this invention is to provide a switch for battery operated hand lanterns which is simple in construction, positive in operation, cheap to manufacture, and easy to operate.

Another object of this invention is to provide a switch which may be readily operated by a person whose fingers are large, clumsy, stiff, or hardened by toil. For instance, it may be readily operated by a man whose fingers are stiff and numb due to exposure to cold. Also, it may be readily operated by a man whose hands are incased in heavy gloves or mittens.

Another object of this invention is to provide a switch which will not accidentally close the electric circuit and exhaust the battery so it will be useless at a time when it is needed.

It is a further object of this invention to provide a switch which is rugged in construction so it will withstand the hard usage or abuse to which battery-operated lanterns and lamps are often subjected.

One form of the mechanism for accomplishing these results is shown in the accompanying drawing in which:

Fig. 1 is a vertical section through the front part of an electric hand lantern showing the improved switch mounted thereon;

Figs. 2, 3 and 4 are, respectively, views of the switch from the left, rear and bottom sides.

In Fig. 1, 11 is the case of a conventional hand lantern; 12 is the bottom section; 13 the top section; 14 is the electric bulb; 15 the reflector; 16 the glass window; 17 the battery; 18 is a conductor which carries current from the battery to the electric bulb; 19 is a conductor which carries the current from the bulb to the switch; and A is the oscillating metal lever of the switch which conducts the current to the case 11 that forms part of the electric circuit and conducts current back to the battery.

The switch comprises two parts, A and B. A is the manually operated, oscillatable circuit closing and opening lever or tumbler and has an outer portion or handle 20, an en-

larged central supporting section 21, and a contact making section 22, which is acted upon by the member B to somewhat control its action. B is the combined supporting, limiting, and controlling member and has a base 23 provided with a bent portion forming a recess 23' in its under side arranged to partially surround the enlarged portion 21 of the lever A. Two resilient members or arms 25, preferably integral with the base and turned rearwardly at its lateral edges, partially surround the contact-making end 22 of the lever A and are bent over the recess 23' and toward one another at 25' so as to form a restricted passage or throat through which the end 22 passes and is urged to the limit of its travel in either direction.

The enlarged central portion 21 of the switch tumbler A may be either cylindrical or globular in shape and preferably fits snugly into a bevel edged opening 21' in the lantern case 11 or other suitable support. This opening is of a size that will permit the handle 20 to freely move through the range of its travel and, at the same time, will not permit the enlarged portion 21 to pass therethrough. The base 23 is secured to the inside of the wall 11 by rivets 24 or otherwise, so that the recess 23' therein forms the rest of the socket to receive the enlargement on the lever A between said base and said wall. A slot 26 in the recess of the base is slightly wider than the diameter of the tumbler section 22 and guides it in its movement in a plane perpendicular to the base 23. The top end of this slot forms a stop which limits the upward travel of the lever. Preferably, the end 27 of the conductor 19 limits the movement of the lever in the downward direction.

To move the switch from closed position, as shown in Fig. 1, to open position pressure is applied at the top of the tumbler handle 20. As the tumbler starts to move, the end 22 separates the resilient controlling members 25 of part B sufficiently to let it pass between them. As the tumbler A nears its open position and the end 22 passes beyond the parts 25', the controlling members 25 of part B move toward each other and, due to their shape, have a camming action on the curved end 22 tending to snap the tumbler to its open position and hold it there. Pressure applied to the under side of the tumbler handle 20 will likewise move it to its closed position with a snap action, and the outwardly bent ends 110

25" of the arms 25 hold the contacting end 22 against the conductor 27.

The shape of the tumbler A and its supporting member B may be changed to meet various 5 conditions without departing from the spirit of this invention. For instance, the shape of the tumbler handle A may be square, hexagonal, cylindrical, or of a shape having an enlarged head portion; the end may be flat or 10 oval and all or part of it may be knurled or otherwise roughened. The central portion 21 of part A may be either round, cylindrical, elliptical, or conical. Also, the attaching surface of the supporting member B may be 15 formed to fit a section of the lantern case which is not a flat surface and the controlling spring portions might be of a shape other than that shown. Furthermore, any convenient number of attaching rivets or other 20 attaching means may be used.

I claim:

1. In an electric switch, the combination 25 with an oscillating lever having a handle at one end, contacting means adjacent its other end, and an enlargement between said ends; of supporting and guiding means for said lever comprising a member having an opening through which said handle projects, a base secured to said member and having a bent portion 30 opposite said opening to receive said enlargement, said bent portion being provided with a slot through which the contacting end of said lever projects and whereby the lever is guided, and an upturned section on 35 the side of said base having a resilient portion extending into the path of said lever.

2. In an electric switch, the combination 40 with an oscillating lever having a handle at one end, contacting means adjacent its other end, and an enlargement between said ends; of supporting and guiding means for said lever comprising a supporting member having an opening through which said handle projects, a base secured to said member having 45 a bent portion opposite said opening to receive said enlargement, an opening in said bent portion through which the contacting end of said lever projects, and arms upturned from the lateral edges of said base and arranged to cooperate with said contacting end. 50

3. In an electric switch, the combination with an oscillating lever, of a support through which said lever projects, a base secured to said support and having a recess in its surface facing said support to provide a socket for 55 a part of said lever, said base having a slot which receives part of said lever and restricts its movement to a plane perpendicular to said base and limits its travel, said base also having resilient members upturned from its sides 60 and cooperating with said lever to snap it into open or closed circuit position.

4. In an electric switch, the combination of a support having an opening therethrough; an oscillating switch lever having a handle 65 projecting through said opening, a contacting portion, and an intermediate portion bearing against said support and closing said opening; a base secured to said support having a socket to receive said intermediate portion 70 and hold it between said support and base; said base having a slot in its socket through which said contacting portion projects and whereby the lever is guided in a plane perpendicular to said support and its travel is limited 75 in one direction, said base also having integral resilient members bent up from the sides thereof between said socket and one end of the base arranged to form a throat to guide said lever and operative to snap said lever to the limit of its travel in either direction; and a contact engageable by said contacting portion and adapted to limit the travel of said lever in one direction.

5. In an electric switch, the combination 80 with a switch lever having a handle at one end, contacting means at its other end, and a transversely disposed enlargement intermediate said ends; of supporting means for said lever comprising two apertured members 85 forming a recess for said enlargement, one of said members having parallel resilient members extending upwardly from the sides thereof in planes substantially perpendicular to said member, said resilient members being 90 shaped to form a constricted opening therebetween.

In testimony whereof, I affix my signature.

RALPH R. SMITH.
